UNITED STATES PATENT OFFICE.

SAMUEL FARQUHAR, OF NEWTON, MASSACHUSETTS.

SASH-FASTENER.

SPECIFICATION forming part of Letters Patent No. 295,530, dated March 25, 1884.

Application filed January 4, 1884. (No model.)

To all whom it may concern:

Be it known that I, SAMUEL FARQUHAR, of Newton, in the county of Middlesex and State of Massachusetts, have invented an Improved 5 Sash-Fastener, of which the following is a full, clear, and exact description, reference being had to the accompanying drawings, making part of this specification, in which—

Figure 1 is a perspective view of a portion 10 of a window-frame and its sashes with my improved fastening device in its locking position applied thereto. Fig. 2 is a perspective view of the rear of my fastening device as seen from the pulley-stile into which it is fitted. Fig. 3 represents a portion of the upper sash, with 15 dotted recesses therein for the fastening-bolt to engage therewith. Fig. 4 is a vertical sectional elevation. Fig. 5 is a horizontal section.

My present invention relates to that class of 20 sash-fasteners located within the pulley-stile, and has for its object to prevent the sashes from being clandestinely opened from the outside; and this invention consists in a spring-actuated or weighted lever pivoted within a 25 frame or casing let in flush with the stile, in combination with a bolt connected with the top of the lever by an arm pivoted to lugs projecting from the casing, the lower end or heel of the lever having an unyielding bearing on 30 the top of the contiguous side of the lower sash, or upon a plate secured thereto, the corresponding side of the upper sash being provided with one or more recesses for the reception of the bolt when the lever is in its locking position, the said fastening being simple and durable, and possessing the ability to resist any 35 attempts to pry up the lower sash or force down the upper sash from the outside.

To enable others skilled in the art to understand and apply my invention, I will proceed 40 to describe the manner in which I have carried it out.

In the said drawings, A represents a portion 45 of a window-frame; B, the upper sash; C, the lower sash; D, the pulley-stile, and E the parting-bead, all of which are of well-known construction.

G is a metal frame or casing, composed of a 50 vertical portion, a, and a horizontal portion, b. Between the sides of the vertical portion a is pivoted, at c, a lever, H, (of the form seen in Fig. 4,) having a slot, d, formed through its

upper end, said slot being for the reception and free play of one end of a horizontal arm, I, pivoted at e between two lugs, h h, projecting from the horizontal portion b of the metal casing, the other end of said arm fitting loosely within a slot, i, in the outer end of a horizontal bolt, L, which passes through a guide, k, formed in the outer end of the portion b of the casing, and enters one of a series of cylindrical recesses, l, formed in the contiguous face of the upper sash, (see Fig. 5,) the said bolt being pressed into said recess by the action of a spring, m, Fig. 4, whose upper end is secured 55 at n to the back of the lever, and whose lower end is free to slide against a stop-pin, p, extending between the sides of the vertical portion of the casing, by which construction the lower end of the lever is pressed in the direction of the arrow, with its heel bearing on a plate, r, set in flush with the top of the lower sash, said lever being in its normal or locking position, Figs. 1 and 4, until pressure is applied upon its lower end against the resistance 60 of the spring when the bottom of the lever is moved in flush with the inner face of its metallic casing, in which position either sash is free to be moved. When the upper sash is lowered sufficiently to bring one of its recesses 65 in line with the bolt, the compression of the spring m is relaxed, the heel of the lever is pressed by the expansion of the spring inward upon the bearing-plate r, and, through the connections described, the bolt is caused to enter 70 the recess in line, and the two sashes are securely locked, the said locking device being effectual in resisting any attempts to raise the lower sash or lower the upper sash from the outside. When the upper sash is to be lowered, 75 so as to secure the ventilation of the apartment, it is simply necessary to press in the lower end of the lever and lower the upper sash until another of its recesses is brought in line with the bolt, when the latter is pressed therein, 80 and the upper sash locked in this position, the lower sash being simultaneously locked by the return of the heel of the lever upon its bearing-plate r. 85

By pivoting the lever G and arm I within 90 the casing, the several parts constituting the device are always at hand, and may be removed and applied at one operation. The spring m may be dispensed with; but in such case the 95

location of the pivot *c* must be changed, so that the weight of the upper end of the lever will cause the lower end to project out of its casing over the lower sash; but I prefer the construction first described.

5 I claim—

The within-described sash-fastener designed to be located in the pulley-stile, consisting of the lever *H*, pivoted to the vertical portion *a* 10 of the casing *A*, and having a slot, *d*, in its upper end, the connecting-arm *I*, pivoted to lugs *h h*, projecting from the horizontal por-

tion *b* of the casing *A*, and the bolt *L*, having a slot, *i*, in its outer end, in combination with the upper sash, *B*, provided with recesses *l*, 15 and the lower sash, *C*, all constructed and arranged as set forth.

Witness my hand this 28th day of December, 1883.

SAMUEL FARQUHAR.

In presence of—

N. W. STEARNS,
JAS. W. CHAPMAN.
